Attys.

UNITED STATES PATENT OFFICE.

HAROLD B. CRANSHAW, OF WEST NEWTON, AND ELBRIDGE HUFF, OF SOMERVILLE, MASSACHUSETTS, ASSIGNEES TO CUTTER MANUFACTURING COMPANY, OF EVERETT, MASSACHUSETTS, A CORPORATION OF MASSACHUSETTS.

FOLDING SCREEN.

Application filed May 24, 1924. Serial No. 715,714.

To all whom it may concern:

Be it known that we, HAROLD B. CRANSHAW and ELBRIDGE HUFF, citizens of the United States of America, and residents of 5 West Newton and Somerville, respectively, both in the county of Middlesex and State of Massachusetts, have invented new and useful Improvements in Folding Screens, of which the following is a specification.

10 This invention relates to screens comprising a framework enclosing a sheet of suitable material and more particularly to fire screens having a plurality of folding sections each comprising a metal framework 15 surrounding a wire netting. One of the objects of the invention is to provide a screen of simple and durable construction having a rigid framework which is economical to manufacture, practically indestructible in 20 use and of pleasing appearance.

The preferred embodiment of the invention comprises in general a plurality of substantially rectangular screen sections pivotally interconnected to form a jointed screen 25 adapted to be placed in extended position or to be folded together when not in use. Since this is a construction common to the prevailing types of fire screens, the construction embodying the present invention is not illustrated in its entirety, but several concrete 30 embodiments thereof are shown in the accompanying fragmentary drawings, in which:

Fig. 1 is a plan view of the corners of 35 two adjoining screen members;

Fig. 2 is a side elevation thereof;

Fig. 3 is an enlarged sectional view on the line 3—3 of Fig. 1;

Fig. 4 is a transverse section on the line 40 4—4 of Fig. 3;

Fig. 5 is a plan view, similar to Fig. 1, of an optional construction;

Fig. 6 is a side elevation of Fig. 5;

Fig. 7 is an enlarged sectional view on the 45 line 7—7 of Fig. 5;

Fig. 8 is a transverse section on the line 8—8 of Fig. 7; and

Figs. 9 and 10 are detail views, showing

the construction of an elbow for use in rectangular frames.

Referring to Figs. 1 to 8 of the drawings, the numerals 11 represent sections of tubing constituting the frame of the screens. These sections preferably consist of a tube of rigid metal, such as brass which also lends beauty 55 to the completed structure, and the ends of the tubing are preferably cut at an angle of approximately forty-five degrees to form a close fitting union between adjacent sections. A longitudinal slot 12, best shown in Figs. 60 4 and 8, extends along the entire length of each section of tubing in such position that the slots in each section will meet, to form a continuous longitudinal opening around the innermost portion of the assembled 65 screen frame.

In order to give greater strength and durability to the screen frame and to insure a tight and practically non-displaceable joint at the corners thereof, there is provided an elbow 13, adapted closely to fit within the tubing 11 at each corner of the frame. The elbows are preferably constructed of hollow angular castings of bronze, or pressed steel, with smoothed, substantially cylindrical 75 surfaces having a diameter approximately equal to the bore of the tubings 11. Slots 14 in the elbows are adapted to register with the slots 12 in the tubing, to constitute means for fixedly retaining therewithin a 80 central screen 15. In connection with means hereinafter explained for fixing the position of the upper and lower frame sections 11 with respect to the elbows 13 and for securing the side frame sections to prevent vertical movement thereof relative to said elbows, the latter also serve to prevent relative dislodgement or separation of the corners of the frame sections, thereby prolonging the useful 85 life of the screen.

The screen 15 is illustrated to consist preferably of a network of wire for use as a fire-screen, but any desired material may be employed to suit the purpose of use. The edges of this screen are preferably stiffened by a 90 strip or strips of metal binding 16 pressed

about said edges, and are adapted to be inserted within the slots 12 and 14, of the tubing and elbows, when the screen is assembled within the framework. The assemblage may 5 be conveniently effected by first uniting three sections of the tubing, then sliding the screen into position through the slots 12 and 14, and finally placing the fourth section, which should carry two of the elbows 13, into position 10 to enclose the screen within the framework. In thus assembling the individual screen sections, it is preferred that the elbows 13 and the bore adjacent the ends of the tubing 11 should be tinned in order that the 15 elbows may be sweated into the tubing, thereby effecting a secure and rigid joint at each corner of the frame. If desired, a small amount of solder may be run between the meeting edges of the tubing at each corner. 20 Two possible constructions for uniting the screen sections to form a folding screen are illustrated in Figs. 1 to 4 and 5 to 8, respectively.

In the first construction vertical rods 17, 25 preferably of brass, extend through the tubing 11 and elbows 13 and project through corresponding holes in said tubing and elbows at top and bottom, where they may be secured in position by nuts 18 threaded to 30 the rods. The rods in adjacent screen sections are interconnected at top and bottom by a rigid metal link 19 adapted to space the said screen sections from each other and to permit each section to be folded flat against 35 its neighbor. Knobs 20 are screwed tightly upon the threaded ends of the rods 17 to restrain vertical movement, but to permit pivotal movements of the links 19.

The second construction comprises a vertical metal rod 20, extending at one end through the central portion of a metal link 21, and preferably peened or soldered within a second similar link at its other end. This rod 20 is adapted to lie between the side 45 frames of two adjacent screen sections, and is pivotally secured to each of said sections by the engagement of holes in either end of said link 21 with projecting vertical pintles 22 carried by set screws 23 which are fastened within threaded holes in the tubing 11 and elbows 13, as shown in Fig. 7. The links are pivotally secured upon their respective 50 pintles by fastening the nut or knob 24 upon the free end of the rod 20. The set screws 23 preferably have hexagonal heads, and it is apparent that they may fasten within 55 threaded holes either in the tubing or in the elbow, or in both.

Although the preceding description has referred 60 to a framework consisting of tubular members it is obvious that rectangular or other shapes of framework may be employed equally as well. In such other constructions the metal elbows should conform in shape to

the bore of the frames, and in case a rectangular elbow is desired, a convenient manner of constructing such elbow is illustrated in Figs. 9 and 10. A metal blank may be cut substantially as in Fig. 9 and may then be folded along the dotted lines to complete the 70 elbow as shown in perspective in Fig. 10.

In either of the constructions heretofore explained it is apparent that the members constituting the pivotal connection between adjacent screen members serve to permit the 75 screen to be folded together and, in connection with the elbows 13, also serve as an aid in maintaining the rigidity and in preventing displacement or separation of the tubing constituting the framework of each screen 80 section. In Figs. 1 to 4, the metal rods 17 pass through the elbow 13 and tubing 11 preventing displacement of the tube unions in a horizontal direction, and the nuts 18, at 85 top and bottom, firmly secure the frames against vertical displacement. Similarly in Figs. 5 to 8, the set screws 23 extending into the elbows 13 prevent separation of the corner joints horizontally; and the links 21 are clamped upon the set screws 23 preventing 90 separation in a vertical direction.

We claim:

1. A folding screen comprising a plurality of screen sections, each having a central screen portion and hollow frames surrounding and fitting about said central screen portion, said frames having meeting ends at the corners of each of said screen members, elbows adapted closely to fit within the meeting ends of said hollow frames to provide a tight and rigid union therebetween, and means for pivotally interconnecting adjacent screen sections, said means interlocking said elbows and frames. 95

2. A folding screen in which each section comprises tubular side and end members meeting at the corners, tubular elbows telescoping with the side and end members at the corners, said members and elbows having slots in their inner sides, a screen fitting into 100 said slots, and means pivotally interconnecting the sections, said means interlocking said members and elbows. 110

3. A folding screen in which each section comprises tubular side and end members meeting at the corners, tubular elbows telescoping with the side and end members at the corners, said members and elbows having slots in their inner sides, a screen fitting into 115 said slots, and means pivotally interconnecting the sections, said means including pivots extending through said ends and thence into said elbows. 120

4. A folding screen comprising a plurality of screen sections, each having a central screen portion and hollow metal frames surrounding and fitting about said central screen portion, said frames having meeting 125

ends at the corners of each of said screen members, elbows adapted closely to fit within the meeting ends of said hollow frames to provide a tight and rigid union therebetween 5 and means comprising pivotal members radially extending through said metal elbows and through at least one of the walls of said hollow frames to prevent relative longitudinal displacement therebetween, and links 10 pivotally secured upon said members for interconnecting adjacent screen members.

5. A folding screen comprising a plurality of screen sections, each having a central screen portion and hollow frames surrounding and fitting about said central screen portion, hollow elbows adapted closely to fit within the meeting ends of said hollow frames to provide a tight and rigid union therebetween, pivots passing through complementary radial holes in the outer walls of said hollow frames and said hollow elbows, to prevent relative longitudinal movement therebetween, and extending upwardly and downwardly from the upper and lower corners 20 respectively of each of said screen sections, metal links interconnecting the respective pivots of adjacent screen sections, and means for retaining said links upon said pivots to secure the said frames rigidly together and to restrain vertical movement of the upper and lower frames with respect to the side frames.

6. A folding screen comprising a plurality of screen sections, each having a central screen portion and hollow frames surrounding and fitting about said central screen portion, hollow elbows adapted closely to fit within the meeting ends of said hollow frames at the corners of said screen sections 35 to provide a tight and rigid union between said frames, longitudinal slots in said hollow frames and slots in said hollow elbows registering with said frame slots, said slots being positioned in the inner side of said frames and elbows and being adapted to receive and retain the said central screen portion, and means for pivotally interconnecting adjacent screen sections whereby they may be folded flat against each other.

50 7. A folding screen comprising a plurality of screen sections, each having a central screen portion and hollow frames surrounding and fitting about said central screen portion, hollow elbows adapted to fit within the meeting ends of said hollow frames at the corners of said screen sections to provide a tight and rigid union between said frames, longitudinal slots in said hollow elbows in registration with said frame slots, said slots 55 being positioned in the inner side of said frames and elbows and being adapted to receive and retain the said central screen portion in fixed position, and means for pivotally interconnecting adjacent screen sec-

tions, said means comprising pivots extending through complementary radial holes in the walls of said hollow frames to prevent relative longitudinal movement therebetween, rigid metal links connecting the respective pivots on adjacent screen members 70 at top and bottom, and means for securing said links upon said pivots to restrain separation of the meeting ends of the said frames in a vertical direction.

8. A folding screen comprising a plurality of substantially rectangular screen sections, each having central wire screen portion and tubular metal frames surrounding and fitting about said central screen portion, said frames having diagonal meeting ends 80 constituting the corners of said screen sections, hollow metal elbows closely fitting within the said tubular frames at the said corners thereof, to provide a tight and rigid joint therebetween, longitudinal slots in the inner wall of said frames and slots in said elbows in registration with said frame slots, said slots constituting means for holding the said central screen portion in fixed position 85 within the frame, pivots passing through complementary radial holes in the horizontal outer walls of said tubular frames and said hollow elbows for preventing relative longitudinal movement therebetween, at least one of said pivots being positioned near each corner of said screen sections and extending outwardly from said frames, metal links interconnecting the said outwardly extending portions of the respective pivots of adjacent 90 screen members, and means for rotatably securing said links upon said pivots to fasten the said frame sections rigidly together and to restrain disengagement of said frame joints.

9. A screen comprising a framework of hollow members meeting at the ends, reinforcing members interfitting with the meeting ends, means extending through adjacent hollow members and the reinforcing member associated therewith to hold the same together, said hollow members and said reinforcing member having slots on their inner sides, and a central screen portion fitting into said slots.

10. A screen comprising a framework of hollow members meeting at the corners, elbows telescoping into the meeting ends, means cooperating with and extending through each pair of meeting ends and the elbow telescoping therewith for holding said parts together, said members and elbows having slots on their inner sides, and a central screen portion fitting into said slots.

11. A folding screen in which each section comprises hollow side and end members meeting at the corners, hollow elbows telescoping with the side and end members at the corners, said members and elbows

having slots in their inner sides, a screen fitting in said slots, and means for pivotally interconnecting the sections including rods extending longitudinally within said end members and passing through said elbows.

12. A folding screen each section of which comprises hollow top and bottom and end members meeting at the corners and hollow elbows telescoping with the side and end

members at the corners, and means for pivotally interconnecting the sections including members extending vertically through said top and bottom members into said elbows.

Signed by us at Boston, Massachusetts, 15 this 21st day of May, 1924.
